UNITED STATES PATENT OFFICE.

JOHN K. STEWART, DECEASED, LATE OF NORTHPORT, NEW YORK, BY JULIA B. STEWART, EXECUTRIX, OF NORTHPORT, NEW YORK.

PUMPING DEVICE.

1,247,892.

Specification of Letters Patent. Patented Nov. 27, 1917.

Application filed October 14, 1916. Serial No. 125,647.

To all whom it may concern:

Be it known that I, JULIA B. STEWART, a citizen of the United States, residing at Northport, in the county of Suffolk and State of New York, am the executrix of the last will and testament of JOHN K. STEWART, deceased, who resided at the time of his death at Northport, Suffolk county, in the State of New York, and who had invented new and useful Improvements in Pumping Devices, of which the following is a specification, reference being had to the accompanying drawings, forming a part thereof.

The purpose of this invention is to provide an improved pumping device particularly designed for pumping liquid fuel or lubricating oil from a low level main supply tank to a higher level supplementary reservoir for furnishing fuel or lubrication to an internal combustion engine, but not limited to this specific use. It consists in the elements and features of construction shown and described as indicated in the claims.

25 In the drawings:—

Figure 1 is a plan view of a device embodying this invention.

Fig. 2 is an axial section at the line 2—2 on Fig. 1.

30 Fig. 3 is a detail section of a modification.

The structure shown in the drawings comprises a casing which is conveniently constructed as shown, comprising an annular wall, A, a back or bottom wall, formed by a plate, B, forced or threaded tight into the annular wall, A, at one side. The opposite wall of the chamber is formed by a flexible diaphragm, C, which is bound in place upon the annular member, A, by means of a top or front plate member, D, screwed into the member, A. The chamber of the casing is partitioned by a second diaphragm, E, which in practice may at one position rest against the inner surface of the wall, B, of the chamber, and is so shown, being bound in place by said wall, B, screwed into the annular member, A. The two diaphragms are connected at their center by a post, F, passing through both diaphragms at the center and bound fluid-tight by any well known means such as clamping nuts, H and H¹. The wall, B, of the chamber has a nipple, B¹, through which there is formed an inlet passage leading into the chamber,

which is conveniently enlarged so as to accommodate the clamping nut, H¹, and also a spring, G, reacting against the shoulder, b¹, formed by the enlargement of the inlet passage, and against the post, F, and diaphragm, E, through the medium of the clamping nut, H¹, for thrusting the post, and thereby both the diaphragms, away from the inlet. The inlet passage through the nipple, B¹, has a check valve, J, which opens for flow inward and may be provided with a spring, j, for seating it in the opposite direction. The post, F, has a passage opening at one end through the side of the post into the inter-diaphragm space, and at 60 the other end through the end of the post in the inlet passage. In the passage of the post there is provided a check valve, L, opening for flow inwardly,—that is, toward the inter-diaphragm space. This check 65 valve may be provided with a spring, l, tending to seat it in the opposite direction. As illustrated, for convenience of manufacture, the post is made in two parts, one part clamped to the diaphragm, C, and the other 70 part clamped to the diaphragm, E, the axial portion of the passage being made in the last mentioned part in which also the check valve is seated, having the spring, l, coiled around its stem in the axial bore of said 75 part of the post, said part of the post being reduced in diameter for a distance from the upper end, and the other end of the post being bored to receive the reduced end portion of the first mentioned part, the two 80 parts having registering radial apertures, 7³ and 7⁴, for completing the passage into the inter-diaphragm space. The top or dia- 85 phragm-clamping member, D, has an exteriorly protruding, and interiorly hollow 85 diametrically extending boss, D², at one end of which there is afforded a seat at d², for the fulcrum of a spring lever, M, which is a flat steel bar elastically flexible, which rests upon the upper end of the post, F, 90 when the latter is at the position to which it is thrust by the spring, G, so that the lever when operated at its free end,—where a notch, m, is provided to indicate means of engagement with any oscillating or re- 95 ciprocating part, not shown, for operating it,—the post is thrust inward and the dia- 100 phragms are thereby forced toward the inlet, being forced back by the reaction of the spring, G, when the lever oscillates in 105 110

the opposite direction. The lever, M, is designed to be merely stiff enough to compress the spring, G, and overcome any desired additional amount of resistance which 5 may be offered by the pressure of a liquid column in the discharge pipe, P, or the reservoir to which it leads. From this characteristic of the construction it will result that when the lever, M, is continuously oscillated, the inlet nipple, B¹, being connected with the liquid to be pumped, the liquid will be pumped up through the inlet and through the post, F, and out through the discharge connection, P, from the inter- 10 diaphragm space, only until the resistance to the inward thrust of the post and inward movement of the diaphragm, due to the pressure of the column of liquid which is being raised and upheld in the discharge 15 pipe and any reservoir to which it leads, exceeds the stiffness of the lever; and then, although the lever continues to oscillate, no pumping will be done until the height of the column is diminished.

20 25 In Fig. 3 there is shown a modification in which the lever is unyielding, but the post, F, is provided with a yielding terminal F¹, against which the lever operates, obviously with the same effect as if the lever 30 were yielding.

I claim:—

35 1. In combination with a casing forming a chamber and having an inlet through one side wall thereof; a diaphragm forming the opposite wall of the chamber, a second diaphragm partitioning the chamber and inclosing at one side a space between it and the first mentioned diaphragm, and at the other side a space between it and the wall 40 having the inlet, the chamber having an outlet for the first-mentioned inclosed space; a post connecting the two diaphragms and having a passage opening at one end in the first mentioned space and at the other end in the second mentioned space; check valves in the inlet passage and in the post passage, both opening for flow toward the inter-diaphragm space, and yielding means for reciprocating the post and thereby vibrating 45 both diaphragms simultaneously.

50 2. In combination with a casing forming a chamber and having an inlet passage

through one wall thereof, a diaphragm forming the opposite wall of the chamber; a second diaphragm partitioning the chamber and inclosing at one side a space between it and the first mentioned diaphragm, and at the other side a space between it and the wall of the chamber having the inlet passage, the chamber having an outlet passage from the inter-diaphragm space; a post connecting the two diaphragms, having a passage opening at one end into the inter-diaphragm space, and at the other end 55 into the other of said spaces; check valves in the inlet passage and in the post passage, both opening for flow toward the inter-diaphragm space; a spring re-acting on the post for thrusting it away from the inlet; yielding means operating upon the opposite end of the post for thrusting it in the opposite direction.

3. In combination with a casing forming a chamber and having an inlet through one wall thereof, a diaphragm formed in the opposite wall of the chamber; a second diaphragm partitioning the chamber and inclosing at one side a space between it and the first mentioned diaphragm, and at the other side a space between it and the wall having the inlet, the chamber having an outlet leading from the inter-diaphragm space; a post connecting the two diaphragms and having a passage which opens 75 at one end into the first mentioned space and at the other end into the second mentioned space; check valves in said passage and in the inlet passage, both opening for flow toward the inter-diaphragm space; a spring which normally holds the diaphragm yielding away from the wall having the inlet passage, and an elastically-yielding lever arm fulcrumed on the casing outside the diaphragm wall of the casing and operating thereon, and adapted to be vibrated 80 for yieldingly forcing the diaphragm inward and permitting it to be returned outward.

40 45 In testimony whereof I have hereunto set 100 my hand at New York, New York county, this 10 day of October, 1916.

JULIA B. STEWART,
Executrix of John K. Stewart, deceased.
